UNITED STATES PATENT OFFICE.

HENRY J. APPLETON, OF DETROIT, MICHIGAN.

ANNUNCIATOR.

1,311,634.

Specification of Letters Patent. Patented July 29, 1919.

Application filed December 4, 1918. Serial No. 265,314.

To all whom it may concern:

Be it known that I, HENRY J. APPLETON, a citizen of the United States, residing at Detroit, county of Wayne, State of Michigan, have invented a new and useful Improvement in Annunciators, of which the following is a specification.

This invention relates to a street car annunciator for use on street cars to indicate the streets as the car passes along its trip. One of the advantages of the invention is to provide apparatus which is positively tripped by devices placed along the route of the trolley. Suitable locking mechanism is provided to insure the non-movement of the indicating apparatus except when it responds to the desired action of the tripping mechanism. Suitable automatic reversing mechanism, adjustable for different lengths of trips, is a further feature of the invention. The details and the nature of the broad improvements will more easily appear when the detailed description of the apparatus is given.

25 In the drawings,—

Figure 1 is a rear elevation of the interior mechanism in the annunciator case taken on the section line 1—1 of Fig. 3.

30 Fig. 2 is a top view of the annunciator case, part of it broken away to show the interior mechanism at the back of the case, taken on the section line 2—2 of Fig. 3.

35 Fig. 3 is a side elevation of the case which is broken away to show the interior mechanism.

Fig. 4 is a detail of the spider switch and the locking wheel.

Fig. 5 is a side elevation of the trip mechanism, the housing being sectioned.

40 Fig. 6 is an end elevation of the same.

Fig. 7 is an end view of the wire tripper that is attached to the trolley wire support.

45 Fig. 8 is a diagrammatic view showing the apparatus after the trip has been operated.

Fig. 9 shows the apparatus at the instant the trip is forced back to its normal position, which stops the operation of the mechanism.

50 Fig. 10 is a plan view of the reversing apparatus for the driving motor.

Fig. 11 is a side elevation of the same.

55 The apparatus is contained in a case *a* and comprises an upper and lower storage roll *b* and *c* on which winds a sign-carrying belt *a* driven by the teeth of the sprocket wheels

f and *g* passing through the perforations *h* in the side of the belt. These in turn are driven by the pinions attached to them meshing with the driving gear *i* which is on the 60 shaft *k* (Fig. 2). This shaft *k* is driven by a chain *m* passing over the gear wheel *n* on the shaft *k* and the driving sprocket *o* on the main shaft.

Now refer to Fig. 1. This driving sprocket 65 *o* is on the shaft *p* which runs through the electro-magnet *q* where it is provided with a sliding plunger *r* carrying the clutch part *s* adapted to engage with the normally continuously running clutch part *t* having the 70 chain connection *u* (Figs. 8 and 9) with the motor *M*. A pair of brackets *v* at opposite ends of the several shafts already described support not only these shafts but some of the sprocket wheels and storage rolls, as will 75 be obvious by inspection of the drawings. The storage rolls are driven by a belt *w* (Fig. 3) which runs over the sprocket wheels *x* attached to the storage rolls *b* and *c* and over the driving sprocket *y* on the shaft *k*. 80

The clutch is automatically shifted when the trip arm *z* has been thrown back, as shown in Fig. 5, by contact with the trip loops *l* which are suspended from the trolley-supporting cross wire *2*. The trip 85 switch housing *3* is supported to swing in the rectangular bracket *4* in the following way—(refer to Fig. 6). The lower end of the bracket is bolted to the trolley pole *5*. At the top of the trolley pole the flange and 90 sleeve *6* are bolted to the trolley pole. This sleeve supports one end of the rock shaft *7*, which is prevented from pulling out of the sleeve by the pin and annular groove *8*. The other end of the rock shaft is supported 95 in the bearing *9* of the bracket *4* and prevented from longitudinal movement by the pin and groove *10*. To this rock shaft is pinned, to turn with it, by the pin *11*, the hanger *12* that carries the switch box *3*. 100 Pinned to the same rock shaft is the end of the arm *13* which carries a wheel *14* that is forced up against the trolley wire *15* by the spring *16*. Obviously this trailing wheel arm and switch box is so mounted that the 105 trip switch box always assumes a position of parallelism with the trolley wire *15* notwithstanding the position of the trolley pole *5*. This is desirable and necessary when the trolley pole is unduly depressed as is often 110 the case when passing under overhead viaducts or through tunnels.

The trip α is made up of two pieces so that by the bolt and slot 17 the length of the trip may be adjusted to the desired position to strike the obstacle 1. The lower end 5 of the trip arm has a slot and pin connection at the end of the solenoid plunger 18, which carries a bus bar 19 adapted to engage with the contacts 20 and 21.

Now refer to Figs. 8 and 9. It will be 10 found from these diagrammatic views that the circuit from these contacts leads around the electro-magnet q that controls the clutch, the electro-magnets 22, and through the battery B. The magnets 22 serve when energized to push up one end of the pivoted locking bar 23 to release the wheel 24 on the driving shaft p —(see Figs. 1 and 3 where this is depicted). A post 25 holds up the pivoted locking bar 23. Hence when 15 the trip is operated simultaneously the drive shaft p is connected with a source of power and the locking wheel 24 is released to allow the revolution of the driving shaft. When it has rotated a quarter of a turn it 20 carries the spider switch 26 (which is loose upon the shaft p) a quarter of a turn until the contact plate 27 bridges the terminals 28, and establishes the electric circuit connected with the terminals, as shown in Figs. 25 8 and 9. This connects with the solenoid 29 in the switch box 3 on the trolley pole. When the solenoid is energized it retracts and causes the trip arm α to go back to normal, as shown in Fig. 9. The locking wheel 30 35 24 drives the spider through the adjustable clips 101 which are slideable along the rim (Fig. 4). This allows the clips and driving relation of the spider switch to be adjustable so that if the sign belt gets out of step with 40 the driving mechanism, the relation of the switch and the driving shaft p can be allowed to bring the sign into step. The retarding spring 102 prevents the spider running ahead of the locking wheel 24. 45 The motor is automatically reversed at determinable periods by means of the movable contacts 30 that are adjustable as shown in the dotted lines along the bracket 31. The contact 32 is in the form of a nut 50 slideable in the bracket 31 by the depending key engaging in the slot in this bracket. The other part of the nut runs on the screw 34 that is driven by the pulley and pulley cord 35 from one of the shafts 36 on which the 55 driving sprockets g are mounted. Referring to Fig. 1, it will be noted that one of these contacts 30 connects with a wire A A, the other contact 30 connects with a wire B B, and these in turn (see Fig. 10) connect with 60 the solenoid sets 37 and 38 respectively, which have their plungers connected by the connecting bar 39 that at its center is connected with the motor switch lever 40. Obviously when the screw causes the nut 32 to 65 come in contact with the right contact 30

of Fig. 1 the circuit is established through B B around the solenoid 38, returning by the wire C C. This throws the lever to the right. The switch nut contacting the left hand contact 30, energizes the solenoid 37 70 and throws the switch 40 on to the left, reversing the motor. Obviously by adjusting the contact 30 along the slot in the bracket 31 the moment that this reversal takes place can be adjustably fixed. 75

Any appropriate means for compensating for the varying peripheral speed of the rolls in varying conditions of the winding of the belt may be adopted. For instance, I have shown in Fig. 1 a familiar way of doing 80 this by utilizing a spring coiled around the roll shaft and fastened at one end of the shaft and at the other end to a pin in the wall of the roll.

What I claim is:

1. In an annunciator, a belt carrying signs, driving mechanism for said belt, a continuously running driving member, a clutch between the driving mechanism and the driving member, a trip switch for contact with obstacles along the way, the said trip switch being of a character to remain tripped after having come in contact with one of said obstacles, connections between the trip switch and the clutch for maintaining the clutch parts in engagement as long as the trip switch remains tripped, and a switch operated by the belt driving mechanism for electro-magnetically returning the trip to its normal open position when the belt has been advanced the desired distance. 90 95

2. In a station annunciator, the combination of a belt carrying signs, driving means for said belt including a reversing lever, a trip switch for contact with obstacles along the way and controlling the action of the driving means upon the said belt, and an automatic reverser comprising a screw driven by the driving means, a nut driven 105 along the screw to make contact with a terminal to close a circuit, said circuit including the said terminal and a solenoid for throwing said reversing lever. 110

3. In a station annunciator, the combination of a belt carrying signs, driving means for said belt including a reversing lever, a trip switch for contact with obstacles along the way and for controlling the action of the driving means upon the said belt, and an automatic reverser comprising a screw driven by the driving means, a nut driven along the screw, a terminal adjustable at various positions along the screw for contact with the nut to complete an electric 115 circuit, and the said circuit including a solenoid for throwing the said reversing lever. 120 125

4. In an annunciator, a sign belt, driving mechanism therefor, a driving member, a clutch between the driving member and the 130

- driving mechanism, a locking member for the driving mechanism, a trip for engaging obstacles along the way, an electric switch connected with the trip, and an electric conductor from the switch terminals and including two solenoids, a lever released from the locking member by one of the solenoids and the other solenoid simultaneously engaging the clutch.
5. In an annunciator, a sign belt, driving mechanism therefor, a driving member, a clutch between the driving member and the driving mechanism, a trip switch for contact with obstacles along the way adapted to electro-magnetically hold the clutch in engagement during the entire time of movement of the belt, and a switch appropriately operated by said driving mechanism for returning the trip to its normal position after the belt has been advanced the desired distance.
10. In an annunciator, the combination of a sign belt, a driving mechanism therefor, a continuously running driving member, a clutch connecting the driving member and the driving mechanism, a trip operated by a car traveling along its way and operative upon the clutch, a switch for restoring said trip to its initial position to disconnect the clutch to stop the driving mechanism, and adjustable connections between the driving mechanism and the said switch to make possible the bringing of the switch and the belt into step in case they get out of step.
15. In an annunciator, the combination of a sign belt, a driving mechanism therefor, a driving member, a clutch connecting the driving member and the driving mechanism, a trip switch for contact with obstacles along the way adapted to electro-magnetically hold the clutch parts in engagement, a locking wheel for the driving mechanism, means for simultaneously releasing the locking wheel with the throwing in of the clutch parts, and an electro-magnetic circuit including a solenoid for returning the trip switch after the belt has been advanced the desired distance and including a controlling switch, terminals and a contact plate for bridging said terminals carried in revolution by the locking wheel and adapted to establish a circuit when the belt has been carried the desired distance of travel.
20. In an annunciator, a sign belt, driving mechanism therefor, a driving member, a clutch connecting the driving member and the driving mechanism, a trip switch for contact with obstacles along the way adapted to electro-magnetically hold the clutch parts in engagement, a locking wheel for the driving mechanism, means for simultaneously releasing the locking wheel with the throwing in of the clutch parts, and an electro-magnetic circuit including a solenoid for returning the trip switch after the belt has been advanced the desired distance and including a controlling switch, terminals and a contact plate for bridging said terminals carried in revolution by the locking wheel and adapted to establish a circuit when the belt has been carried the desired distance of travel.
25. In an annunciator, a sign belt, driving mechanism therefor, a driving member, a clutch connecting the driving member and the driving mechanism, a trip switch for contact with obstacles along the way adapted to electro-magnetically hold the clutch parts in engagement, a locking wheel for the driving mechanism, means for simultaneously releasing the locking wheel with the throwing in of the clutch parts, and an electro-magnetic circuit including a solenoid for returning the trip switch after the belt has been advanced the desired distance and including a controlling switch, terminals and a contact plate for bridging said terminals carried in revolution by the locking wheel and adapted to establish a circuit when the belt has been carried the desired distance of travel.
30. In an annunciator, the combination of a sign belt, a driving mechanism therefor, a continuously running driving member, a clutch connecting the driving member and the driving mechanism, a trip switch for contact with obstacles along the way adapted to electro-magnetically hold the clutch parts in engagement, a locking wheel for the driving mechanism, means for simultaneously releasing the locking wheel with the throwing in of the clutch parts, and an electro-magnetic circuit including a solenoid for returning the trip switch after the belt has been advanced the desired distance and including a controlling switch, terminals and a contact plate for bridging said terminals carried in revolution by the locking wheel and adapted to establish a circuit when the belt has been carried the desired distance of travel.
35. In an annunciator, the combination of a sign belt, a driving mechanism therefor, a driving member, a clutch connecting the driving member and the driving mechanism, a trip switch for contact with obstacles along the way adapted to electro-magnetically hold the clutch parts in engagement, a locking wheel for the driving mechanism, means for simultaneously releasing the locking wheel with the throwing in of the clutch parts, and an electro-magnetic circuit including a solenoid for returning the trip switch after the belt has been advanced the desired distance and including a controlling switch, terminals and a contact plate for bridging said terminals carried in revolution by the locking wheel and adapted to establish a circuit when the belt has been carried the desired distance of travel.

In witness whereof I have hereunto set my hand on the 25th day of November, 1918.

HENRY J. APPLETON.
